UNITED STATES PATENT OFFICE.

SAMUEL BERGSTEIN, OF MIDDLETOWN, OHIO.

PAPER BOX.

1,426,948.

Specification of Letters Patent. Patented Aug. 22, 1922.

Application filed November 17, 1921. Serial No. 515,804.

To all whom it may concern:

Be it known that I, SAMUEL BERGSTEIN, a citizen of the United States, and a resident of Middletown, in the county of Butler and State of Ohio, have invented a new and Improved Paper Box, of which the following is a description.

My invention relates more particularly to the type of box generally known as the Japanese style consisting of an inner tray or box body and an outer box part or cover, the two being formed similarly but of slightly different sizes. The boxes in question are folded from a scored blank having a main panel to form the bottom or top, side panels, and end panels extending straight from the ends of the main panel, the side panels having end extensions to fold in at the ends.

The object of my invention is to provide side extensions in connection with the end panels scored to be folded and lie against the sides of the box at the interior.

Reference is to be had to the accompanying drawing forming a part of this specification, it being understood that the drawings are merely illustrative of one example of the invention.

Figure 1 is a plan view of the box in knocked down or unfolded form;

Figure 2 is a box body shown partly erected;

Figure 3 is a longitudinal vertical section taken through the cover or outer member of the box.

The box to which the invention relates is formed from an oblong blank having a central main panel 10 to constitute the bottom or top of the box, side panels 11 defined by longitudinal score lines 11^a, and end panels

12, 12^a, defined at the base adjacent to the main panel 10 by a score line 12^b, the respective panels 12, 12^a being defined by a score line 12^c.

The box in question has smaller panels 13 at the terminals of the end panels 12, 12^a. Also, in the box in question the side panels 11 have end extensions 14 formed by score lines 15 at their bases. The end panels 12, 12^a, fold at an intermediate score line 12^c to lie respectively at the outer side and inner

side of the ends of the box and with the terminal panels 13 lying flat on the top of the box at the end. The features referred to are known.

In giving the box an erect form the extensions 14 of the side panels 11 are folded laterally inward, the extensions at each end overlapping and the end panels are first folded on the score line 12^b to dispose the adjacent panel section 12 at the outside of the inwardly folded panels 14 and the end panels 12^a with the terminals 13 thereon are now folded on the score lines 12^c so that the panel portions 12^a lie at the interior of the box at the inside of the folded extensions 14, the terminals panels 13 lying flat against the main panel 10 at the interior.

In accordance with my invention I provide side extensions 16 on the end panel sections 12^a inward of the terminal panels 13, whereby said extensions 16 may be folded on the score lines 17 at the bases thereof to lie against the sides 11 at the interior of the box as clearly shown at the right of Figure 2 and in Figure 3, whereby the box is very materially strengthened. The positions of the extensions 16 are such that the terminal panels 13 will lie in the box against the said extensions and have an increased strengthening value.

The strengthening extensions 16, it will be observed, are provided without increasing the cost of material since their presence in the box does not necessitate a blank of increased size.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claim.

Having thus described my invention, I claim:

A box of the class described having side and end panels, these side panels being scored transversely to form flaps adapted to cover and reinforce the entire surface of the end walls of the box, the end panels being also scored transversely to provide flaps adapted to lie on the bottom of the box, each of said last-mentioned panels being also provided with side flaps adapted to cover and reinforce substantially the entire surface of the side walls of the box.

SAMUEL BERGSTEIN.
